UNITED STATES PATENT OFFICE.

JOHN F. FISHER AND WALLACE R. GILLAM, OF PHOENIXVILLE, PENNSYLVANIA, AS
SIGNORS TO THE PHILADELPHIA RUBBER WORKS COMPANY, OF WILMINGTON,
DELAWARE, A CORPORATION OF DELAWARE.

METHOD AND APPARATUS FOR REFINING RECLAIMED RUBBER.

Application filed February 28, 1928. Serial No. 257,678.

This invention relates to procedure and apparatus for refining reclaimed rubber by passing it between closely set mill rolls, to crush and plasticize the small lumps or granules in the stock and reduce it all to substantially the same texture or consistency. The stock is sheeted in its passage between the rolls and the side margins of the sheet contain coarser particles or granules than the rest of the sheet, which probably is because of the fact that the rolls are slightly crowned with a view to maintaining a close setting of the rolls throughout their length notwithstanding the slight springing of the rolls under the very high pressure of the stock passing in a thin film or sheet between them, the crowning of the rolls perhaps being somewhat excessive and the particles in the bank of stock apparently migrating toward the ends of the rolls as an incident of being repeatedly or continuously rejected at the nip of the rolls.

The granular margins of the sheet require to be passed again through the mill to reduce them to the proper state and to this end the common practice has been to scrape them from the roll upon which the sheet is carried at a different position from that at which the main, middle portion of the sheet is scraped from the roll, so that they may readily be separated from the properly refined stock, and because of their highly granular character they have produced variations in the grade of the stock in which they have been given their second passage through the mill, especially since, so far as we are aware, no effort has been made, prior to our invention, to effect a uniform, proportional distribution of them in the new stock with which they are mixed in their second passage through the mill.

Another cause of non-uniformity in the finished stock has been the escape of highly granular stock past the dams at the ends of the mill and the unintended mixing of such stock with the finished product as the trimmed marginal strips, with lumps of the granular stock insecurely hanging to them, are lifted back into the mill.

Our chief objects are to provide uniformity in the refined product; to provide procedure and apparatus whereby the better product may be had with less labor than heretofore has been required for producing

the less uniform and less desirable product; and to increase the production of the mill.

Of the accompanying drawings:

Fig. 1 is a transverse section of a mill embodying and adapted to carry out our invention in its preferred form.

Fig. 2 is a front elevation of the same.

Fig. 3 is a fragmentary plan view of the mill.

Fig. 4 is a perspective view of a scraping knife and its mounting constituting a part of the apparatus.

Fig. 5 is a perspective view of a part of the bin adapted to receive the refined stock.

Referring to the drawings, the mill comprises the usual pair of rolls 10, 11 mounted in end standards 12, 13 and provided with the usual driving means. The knife assembly 14 for scraping the middle zone 15 of sheeted stock from the roll 10 and the bin 16 for receiving the finished stock scraped from the roll by the knife structure 14 also are in general of the usual construction.

We have discovered that escape of stock from the stock bank 17 in the mill through the small clearance space between splice plate 18 and the rolls may be substantially prevented and the granular condition of the side margins of the sheet also may be materially reduced by radically increasing the width of the splice as compared with the prior art, although the clearance between the splice plate and the rolls be permitted to remain the same.

Having thus provided means for producing sheeted stock having side margins comparatively free from coarse granules and clinging granular particles we provide means whereby the marginal strips conveniently may be removed from the roll 10 separately from the sheet 15 of finished stock and fed back into the mill in suitable proportion to the successive charges of new stock and so as to be well intermixed with the latter in again passing through the nip of the rolls.

For this purpose, and also to prevent dirt and particles of new stock from being dropped onto the accumulation of finished stock in the bin 16 as the successive charges of stock are placed in the mill, we provide an inclined shield and table 21 over the bin 16 with its lower margin extending close to the roll 10 just over the knife structure 14, the member 21 being adapted to receive accumu-

- lations of side margin stock 22 scraped from the roll 10 by scraping knives 23, 23 mounted upon respective brackets 24, 24 near the respective ends of the roll over the table member 21. Each knife bracket 24 is preferably formed with a projecting plate 25 extending away from the roll 10 in such position at the inner end of the knife that any part of the accumulated marginal stock re-adhering to 5 the roll 10 and starting to be lifted thereby toward the bank 17 of stock in the mill will be snubbed about the plate 25 and thus caused to break its adhesion to the roll and drop back into the accumulation of stock, 10 the plate thus causing the stock as it accumulates to be rolled into a roughly ball-shaped mass.

As the marginal stock may be allowed to accumulate locally at the ends of the roll the 20 knife may be formed with a straight scraping edge, which is preferable to employing an obliquely disposed knife requiring a scraping edge curved in three dimensions to fit the roll.

25 We preferably provide means such as the removably mounted clips 26 upon the bin 16, at the upper corners thereof adjacent the roll 10 and extending nearly to the roll and to the knife, to prevent crumbs of stock, especially such as are carried by the roll or form at the end of the knife, from dropping into the refined stock in the bin. The clips are removably mounted to permit easy removal of the knife.

35 In the operation of the apparatus, charges of new stock of equal size are brought from a suitable source at substantially equal intervals of time, as determined by the size of the bank 17 in the mill, and as each new charge 40 of stock is brought to the mill it is laid upon the inclined table 21, where the accumulations of marginal stock 22 adhere to it, and the combined mass is pressed against the roll 10, which carries it over to the bank 17, 45 the plates 25 serving to effect a cutting or breaking of the accumulation of marginal stock from that still spread upon the roll, so that a new accumulation will form and be rolled into a ball.

50 As the strips of marginal stock 22 accumulate upon the table at a substantially uniform rate each of the periodically presented charges of new stock, each of standard size, carries with it into the bank 17 a suitably 55 proportioned amount of the marginal stock, and as each installment of the marginal stock goes into the bank with a comparatively large amount of the new stock it undergoes an intermixing therewith in the 60 bank while the bank is large and becomes thoroughly distributed therein before passing again through the nip of the rolls.

65 Thus the several advantages set out in the above statement of objects are obtained, the proper feeding back of the marginal stock

being reduced to a mere matter of feeding the mill with equal charges of new stock at intervals determined by the size of the bank and the proportioning of the marginal and the new stock being automatic. The labor 70 of separately handling the marginal stock and of gathering up droppings is eliminated, as is also the contamination of the finished product.

As modifications are possible within the 75 scope of our invention we do not wholly limit our claims to the specific apparatus or to the exact procedure herein described.

We claim:

1. The method of refining reclaimed rubber which comprises passing the rubber through a mill to form it into a continuous sheet, continuously dividing the sheet lengthwise into strips and causing the strips to accumulate in different piles to separate different grades of stock contained in the sheet, and from time to time feeding successive accumulations of one of the grades of sheeted stock back into the mill with proportional amounts of new stock. 90

2. A method as defined in claim 1 in which successive charges of new stock of substantially the same size are passed into the mill at approximately equal intervals of time and are combined with the corresponding accumulations of the sheeted stock fed back to the mill. 95

3. The method of refining reclaimed rubber which comprises passing the rubber through a mill to form it into a continuous sheet, continuously dividing the sheet lengthwise into strips to separate stocks of different grades contained in the sheet, and feeding the stock of one grade back into the mill substantially in constant ratio to the feeding of new stock into the mill. 100

4. A refining mill comprising a pair of rolls, a plurality of knives adapted to scrape respective zones of the sheeted stock from one of the rolls, means for supporting apart from each other the accumulations of stock from the respective knives, one of the supporting means being adapted to support the accumulation of stock therefrom in position conveniently to be combined with a charge 110 of new stock being passed to the mill, and end-dam members for the mill rolls each of such width in proportion to its clearance with relation to the rolls as substantially to prevent the escape of stock through the 115 clearance space.

5. A refining mill comprising a pair of rolls, a plurality of knives adapted to scrape respective zones of the sheeted stock from one of the rolls and means for supporting apart from each other the accumulations of stock from the respective knives, one of the supporting means being adapted to support the accumulation of stock therefrom in position conveniently to be combined with a 120 125 130

charge of new stock being passed to the mill.

6. A refining mill comprising a pair of sheeting rolls, a scraper for removing the middle zone of the sheet of stock from one of the rolls, a table member mounted over said scraper, and a pair of scrapers for removing the marginal zones of the sheet from the roll at such positions that the stock of the said zones will accumulate upon the said table member.

7. A mill as defined in claim 6 in which each of the last mentioned scrapers is formed with a straight scraping edge.

8. A refining mill comprising a pair of rolls, a knife adapted to scrape a strip of sheeted stock from one of said rolls, means for supporting an accumulation of stock from said scraper, and a member so formed and positioned that stock of the said accumulation adhering to the roll will be snubbed about the said member and thus caused to break its adhesion to the roll.

In witness whereof we have hereunto set our hands this 20th day of February, 1928.

JOHN F. FISHER.
WALLACE R. GILLAM.
